UNITED STATES PATENT OFFICE

97,357

DESIGN FOR A COOK STOVE

Charles J. Rogers, Cicero, Ill., assignor to Crown
Stove Works, Cicero, Ill., a corporation of Illinois

Application August 5, 1935, Serial No. 57,954

Term of patent 7 years

To all whom it may concern:

Be it known that I, Charles J. Rogers, a citizen of the United States, residing at Cicero, county of Cook, and State of Illinois, have invented a new, original, and ornamental Design for a Cook Stove, of which the following is a specification, reference being had to the accompanying drawing, forming a part thereof.

The figure is a perspective view of a cook stove embodying my new design. The other end of the stove is like that shown.

I claim:

The ornamental design for a cook stove substantially as shown and described.

CHARLES J. ROGERS.
